UNITED STATES PATENT OFFICE.

FRANCIS J. STRAUB, OF NEW KENSINGTON, PENNSYLVANIA.

BLOCK FILLING AND MOLDING APPARATUS.

Application filed November 16, 1926. Serial No. 148,673.

My invention refers to improvements in the manufacture of concrete blocks and the like, made of any suitable aggregate and binding material. Ordinarily, such articles are 5 formed by molding the plastic or wet raw material within the mold of a usual stripper block machine having the customary cores, vertically moving ejecting mechanism, etc., as is commonly used in the art.

10 Ordinarily, the surplus material is removed from the top of the mold after tamping by striking of the excess down to the level of the top edges of the mold, and then smoothing and finally leveling the top of the block 15 by lowering a finishing plate and driving it down to the final level of the mold top by the usual tamps.

It frequently happens in such operation that the ends, or one or more of the corners of 20 the block in the mold do not finish up true and level with the middle, and at the edges, due to failure to fill the mold sufficiently at such parts, or for other reasons. The result of such 25 inequality is that the corners are not filled out true and with the proper density, resulting in imperfect articles when hardened.

My invention overcomes this objection by reinforcing the upper ends or corners of the block by a limited amount of surplus material, 30 which is left higher than the main level of the block and which is compressed into such portions by the final pressing action of the finishing plate.

The invention is illustrated in the accompanying drawings, in which:

Fig. 1 is a view in perspective, showing the upper portion of a standard block mold adapted to carry out the operation;

Fig. 2 is a similar view in side elevation, 40 showing the finishing hopper in position;

Fig. 3 is a perspective view of the hopper;

Fig. 4 is a perspective view of the formed unit as it is shaped in the mold after scraping off the surplus by the hopper;

Fig. 5 is a view of the final pressed block, 45 indicating the reinforced upper ends and corners;

Fig. 6 is a diagrammatic view in perspective, showing the outline configuration of a block before compression, with projection of the corners only;

Fig. 7 is a perspective detail view showing a supplemental scraper.

Referring to the drawings, 2 are the side 55 walls, and 3 the end walls, of a block molding

machine, omitting the usual cores and other customary working parts.

Inwardly of the end walls for any desired distance, the side walls are lowered, as by beveled depressions 4, or otherwise shaped 6 down to a lower level defined by the intervening side wall edges 5. These are on a common lower level at each side, so that surplus material above the level of the several edges may be removed clear across from one side to the 65 other.

Such removal is effected by the lower edges of a hopper 6, the lateral dimensions of which correspond generally to those of the mold. The side and end walls 7, 8, of the hopper 70 preferably diverge upwardly, as shown, depending downwardly along the middle, as at 9, below the shallower end portions 10, with the intervening connecting bevel or curve 11, so as to conform to the shape of the top 75 edges of the side walls 2 of the mold when placed thereon, as in Fig. 2.

In such position, the ends of the hopper rest slidably on the opposite ends of the mold so that, after it is filled and tamped, the surplus may be removed by sliding the hopper over laterally, to one side or the other. In such movement, the rear side wall of the hopper will plane off and remove any material 80 above the edges of the side walls, leaving the 85 formed block before final pressing, with upwardly extending ends, as in Fig. 4.

Thereafter, such upwardly extending portions, which are normally of the same general 90 consistency as the remainder of the formed 90 block, are pressed downwardly by the pressing plate in the usual way, bringing the top surface of the block to a common general level, as in Fig. 5.

The surplus material at the ends and corners is thus incorporated into the main end and corner portions of the block, with a corresponding increased compactness or density thereof at such portions, which are otherwise ordinarily incompletely filled or compacted.

The block as a whole, due to such reinforcement, is ejected from the machine in the usual way, and with a greatly improved condition as to its symmetry and finish, so that when 105 hardened, the resulting block is much more nearly perfect. The reinforced ends and corners, and their increased density, with sharpness of edge and continued finish of the surface at all points, is shown in Fig. 5, the 110

shaded parts of which indicate the reinforced portions.

- While ordinarily the removal of the surplus across the middle of the top of the block by movement of the hopper in one direction only is usually sufficient to effect the desired purpose, reinforcement of the corners only may also be accomplished by a supplemental lateral movement of a scraper 12, as in Fig. 7.
- Such scraper is similarly shaped as to its lower edge portion so as to remove corresponding portions between the corners lengthwise of the block as well as sidewise. In such case, the hopper may be moved laterally of the block in the manner described, with supplemental wiping by scraper 12, leaving projecting corner portions only, as clearly indicated in Fig. 6.

In such case, the corner portions are compressed into the main body of the block by the pressing plate, bringing it to a common level in the same way as above described. Such corner reinforcement only may be utilized in connection with any cubical shape, as indicated in Fig. 6.

In the case of square blocks, the hopper and mold are, of course, of the same length and width, so that a square hopper may be used first in one direction and then, after turning one quarter way around, in the other. In such case, the lowered portion 9 will operate both lengthwise and crosswise, as described.

The general construction of the mechanism and its operation will be readily understood from the foregoing description, and it may be applied and used in any of the well known standard designs of block making machinery, or may be changed or varied by the skilled mechanic to adapt it to varying constructions, shapes and installations.

The desired resulting effect of continuous uniformity as to surface and edges, with reinforcement of the physical body portion of the block where it is usually weak or insufficient, greatly adds to the appearance, efficiency, and standardization of building blocks of the kind involved.

What I claim is:

1. In block molding apparatus, a lower mold having its upper edges located in varying horizontal and inclined planes, and an open bottom filling hopper having side walls with their lower edges conforming thereto and movable across the upper edges of the mold.

2. In block molding apparatus, a lower

mold having its upper edges located in varying horizontal and inclined planes, and an open bottom filling hopper having side walls with their lower edges conforming thereto and resting thereon and adapted for sliding movement over the top of the mold for removal of surplus.

3. In block molding apparatus, a lower mold having its upper edges at opposite sides depressed below the outer end portions of the mold top with intervening inclined edge portions, and an open bottom filling hopper having its side walls slidably mounted thereon with their edges conforming to the edges of the mold.

4. In a block molding apparatus, the combination of a lower rectangular block forming mold having vertical side and end walls with the end walls and adjacent short portions of the side walls on a common maximum height level, the middle edge portions of the side walls being lower than said end walls and short portions, with sloping edge portions connecting such depressed middle edge portions of the sides with their maximum height portions providing elevated material cavities at each end of the mold, and an open bottom filling hopper for the mold having sides and ends provided with lower edges conforming to the form and planes of the upper edges of the mold for filling and movable laterally thereover for removal of surplus aggregate above the upper edges of the mold.

5. In a block molding apparatus, the combination of a lower rectangular block forming mold having vertical side and end walls with the end walls and adjacent short portions of the side walls on a common maximum height level, the middle edge portions of the side walls being lower than said end walls and short portions, with sloping edge portions connecting such depressed middle edge portions of the sides with their maximum height portions providing elevated material cavities at each end of the mold, and an open bottom filling hopper for the mold having outwardly flaring sides and ends provided with lower edges conforming to the form and planes of the upper edges of the mold for filling and movable laterally thereover for removal of surplus aggregate above the upper edges of the mold.

In testimony whereof I hereunto affix my signature.

FRANCIS J. STRAUB.
